[57] CLAIM

The ornamental design for a balancing ornament, as shown and described.

DESCRIPTION

FIG. 1 is a perspective view of a balancing ornament showing my new design;

FIG. 2 is a right side elevational view with the left side being a mirror image thereof;

FIG. 3 is a top view thereof;

FIG. 4 is a bottom view thereof;

FIG. 5 is a front view thereof;

FIG. 6 is a rear view thereof;

FIG. 7 is a perspective view of a second embodiment of FIG. 1;

FIG. 8 is a right side view of FIG. 7, the left side being a mirror image;

FIG. 9 is a top view of FIG. 7;

FIG. 10 is a bottom view of FIG. 7;

FIG. 11 is a front view of FIG. 7; and,

FIG. 12 is a rear view of FIG. 7.

The broken line showing of a pedestal and balancing point attached thereto are for illustrative purposes and form no part of the claimed design.
